DESIGN FOR A COMBINED BINOCULAR MAGNIFIER AND PROTECTOR

Leon Gainsborg, New York, and George Swikart,
Yonkers, N. Y.

Application December 16, 1943, Serial No. 112,015

Term of patent 7 years

To all whom it may concern:

Be it known that we, Leon Gainsborg, residing at No. 605 West 170th Street, county of New York, city and State of New York, and George Swikart, residing at No. 568 Palmer Road, Yonkers, county of Westchester, State of New York, citizens of the United States, have invented a new, original, and ornamental Design for Combined Binocular Magnifiers and Protectors, of which the following is a specification, reference being had to the accompanying drawing, forming part thereof.

Fig. 1 is a plan view of a combined binocular magnifier and protector showing our new design;
Fig. 2 is a front view thereof; and
Fig. 3 is a side view of same.

We claim:

The ornamental design for a combined binocular magnifier and protector, substantially as shown.

LEON GAINSBORG.
GEORGE SWIKART.
